DISHWASHER

Filed July 22, 1927

Agnes J. Poteet
INVENTOR.

BY Ernest A. Hood

ATTORNEY.

UNITED STATES PATENT OFFICE

AGNES J. POTEET, OF DALLAS, TEXAS

DISHWASHER

Application filed July 22, 1927. Serial No. 207,625.

This invention relates to certain new and useful improvements in household utilities and it refers more particularly to an apparatus for washing dishes, pots, pans, cutlery and the like, its principal object residing in the provision of such an apparatus of simple and economical construction adapted to contain a suitable soap or detergent of a solvent character, and attachable to the conventional sink faucet to establish water circulation through the container, and by which hot or cold soapy water is provided, affording a quick and sanitary means of cleansing dishes.

Another object of the invention resides in the provision of a novel valve arrangement by which to by-pass the water to escape the soap container when it is desired to rinse the dishes to remove soap therefrom.

Still another object of the invention resides in the provision of flexible hose connections to facilitate connection to the faucet, and to permit of universal application of the discharge, and upon the end of the latter is provided a brush applicator to enable the operator to cleanse the dishes without necessity of immersing the hands in the hot soapy water.

With the foregoing objects as primary, other objects and advantages, as well as novel features of construction and arrangement of parts will become manifest as the description proceeds, taken in connection with the accompanying drawings wherein:

Figure 1 represents a front view of an apparatus constructed according to the present invention.

Figure 2 is a side view of the invention.

Figure 3 is a fragmentary view showing

the valve and soap container in vertical section.

Figure 4 is a view of the invention applied to the conventional household sink, and

Figure 5 is a detail view in section of the faucet connection.

Continuing now more in detail with the invention, the character 1 designates preferably a square container for soap, the latter being inserted through opening, having a

screw cover provided with wings for convenience, as shown.

The novel triple valve embodying the invention is illustrated clearly in Figure 3 and is composed of a housing 3, secured by screws 4 to the annular rim 5, encircling the opening *a* in the soap container 1, and for reasons later explained, the sides of the housing are arranged at a slight angle as shown.

The housing is provided with an inlet 6 and an outlet 7, respectively, into which are threaded nipples 8. The flexible hose 9 is secured by clamp 10 to the nipple 8 on the inlet side, and, as apparent in the reduced view, Figure 4, is adapted to be connected to the faucet 11, supplying either hot or cold water as desired. The hose 12, connected to the outlet 7, may be of any suitable length and carries upon its end, as also apparent in Figure 4, a brush applicator 13, preferably of the construction shown, but which may be replaced by other types of brushes to suit different occasions.

The valve body 14, having an integral operating stem 15, is mounted within the housing 3, and its sides being likewise arranged at a slight angle, conforms with the shape of the housing. The valve body is provided with opposed bores 16 and 17, extending upward from the bottom and out through the side in such manner as to communicate with the inlet and outlet 6 and 7 as shown, when it is desired to pass the water through the container 1. In order to insure thorough circulation of water through the container to obtain the best results through dissolving the detergent within the container 1, a short pipe 18 is threaded into the inlet bore 16, and depends within the container as shown. The water circulation is thus established as indicated by the arrows in Figure 3, carrying with it through the bore 17 and hose 12 the soapy water mixed by the swirling action of the water within the container 1.

A passage 19 is made through the center of the valve body 14 at right angles to the bores 16 and 17, and upon turning the valve body 14 to register this passage with the inlet and outlet 6 and 7, a bypass for the water is pro-

vided by which the articles being cleaned may be rinsed with clear water.

To prevent undue dissolution of the soap by water remaining in the container 1, a drain plug 20 is provided in the bottom of the latter.

The top of the valve housing 3 has integral therewith an exteriorly threaded nipple 21, leaving an annular space between it and the valve stem 15. Within this space is placed a packing 22. A collar 23 is urged against this packing to compress the same by the cap 24 threaded upon the nipple 21 referred to.

To maintain positive alinement of the passages in the valve with the inlet and outlet 6 and 7 in the valve housing, an expansive spring 25 surrounds the valve stem between the cap 24 and a nut 26 near the top of the valve stem. The action of this spring tends to impart a constant upward urge on the valve body 14, maintaining a close fit between the latter and its housing 3, due to the modified conical formation of these elements as illustrated and referred to previously. A conventional handle 27 is applied as shown, to the top of the valve stem 15, to operate the same. In Figure 5 is shown a detail view in section of a hose connection by which the hose 9 is applied to the faucet, and is composed of a cup 28 having secured in its top a rubber disc 29, centrally apertured to receive the mouth of the faucet 11 as fragmentarily shown. No novelty is herein claimed for this connection, but is shown merely to illustrate the preferred manner of application.

Accordingly and in operation, the improved dish washer is mounted substantially in the position shown in Figure 4 where the sink arrangement permits, and the hose 9 connected with the faucet 11, supplying either hot or cold water as desired. The filler cap 2 is removed and a quantity of soap dropped into the container and the cap replaced.

For better results, a wire mesh basket with a multiplicity of compartments may be employed in connection with the invention in order that the dishes may be supported in a position to drain when washed, and to hold them in a more accessible position for application of the brush 13.

The handle 27 is turned to one extreme to aline the bores 16 and 17 with the inlet and outlet 6 and 7 respectively. The water thus enters the container and the swirling action thereof agitates the soap and creates a mixture, which passes through the hose 12 and into the brush 13, which is applied to the article to be cleansed.

After thoroughly washing the dishes, the handle 27 is moved to the other extreme to aline the lateral passage 19 with the inlet and outlet. The water thus bypasses the container and the soap is undisturbed, permitting the articles to be rinsed with clear water.

It is obvious from the foregoing that dishes and similar articles may be thoroughly

cleansed in a strictly sanitary manner without requiring that the hands be immersed in the hot soapy water.

Manifestly, the construction shown is capable of considerable modification, and such modification as is in keeping with the appended claims is considered within the spirit of the invention.

What is claimed is:

1. The combination in a fluid mixing apparatus of a detergent container having an opening in its top and a drainage port; a valve casing mounted over said opening having an inlet and an outlet; a valve member arranged in said casing and capable of rotation and having a fluid passage connecting said inlet with the interior of said container, and a fluid passage connecting the interior of said container with said outlet; said valve member also having a fluid passage adapted to connect said inlet and outlet to bypass clear water through the machine, means to discharge ingressing fluid near the bottom of said container and means to effect rotation of said valve member to selectively register said fluid passages with said inlet and outlet. 90

2. The combination in a fluid mixing apparatus of a detergent container having an opening in its top and a drainage port, and further having a filler opening forwardly of said first opening; a tapered valve casing arranged on said first opening having an inlet and an outlet; a correspondingly tapered valve member in said casing having a fluid passage to effect communication between said inlet and container, and further having a fluid passage to effect discharge of mixed fluid from said container; said valve member also having a fluid bypass to effect communication between said inlet and outlet; means connected to said first passage to effect discharge of fluid into said container at a point near its bottom; means to rotate said valve member and means to normally impart upward urge to said valve member to maintain snug relationship between the latter and its casing. 100

3. A dish washing machine comprising a container provided with a relatively large opening in the upper side thereof, a valve housing attached to said container and registering with said opening, a valve rotatably mounted in said housing and provided with a stem projecting loosely through the upper part of said housing for operating the valve, said housing having lateral inlet and outlet openings, said valve having an inlet opening adapted to register with the inlet opening of said housing and an outlet opening adapted to register with the outlet opening of said housing and having openings in the lower part thereof communicating with said inlet and outlet openings for circulating fluid through said container, and having a horizontal opening therethrough adapted to com- 110 120 125 130

municate with said inlet and outlet openings simultaneously for circulating clear water for rinsing purposes, and a pipe screwed into said valve for receiving fluid from said inlet openings and for mixing or stirring the water and the detergent.

In testimony whereof I affix my signature.
AGNES J. POTEET.
